COUNTER SALES BOOK

Edward Hano, George U. Lacroix, and George Hogan, Holyoke, Mass.

Application July 10, 1934, Serial No. 734,518

5 Claims. (Cl. 282—12)

Our invention relates to improvements in counter sales books.

An object of our invention is to provide a counter sales book in which an original sheet and 5 one or more copies, made up in sets and attached in continuous fold pack or zig-zag form, may be used, pulled thru and torn off, and replaced by a second set, ready for use.

A further object of our invention is to provide 10 a counter sales book in which continuous fold pack or zig-zag manifolding forms may be used in cooperation with a single set of transfer sheets. Existing practice in the trade is to use a bound book of printed forms, in cooperation with loose 15 transfer sheets which must be removed each time a slip is made out, and replaced between the sheets of the next set of forms. It is our purpose in this invention to eliminate this waste of time and labor by providing means for using a single 20 set of transfer sheets secured in place in such a manner that they will remain in place during the use of a complete set of manifolding forms, to be renewed only when the book is loaded with a new set or book of fold pack forms.

25 A still further object of our invention is to provide a counter sales book for use in cooperation with fold pack or similar manifolding forms which is extremely simple in construction, economical of manufacture, very compact and light 30 of weight, and easy to reload.

These and other objects and advantages of our invention will be more completely disclosed and described in the specification, the accompanying drawings, and the appended claims.

35 Broadly, our invention comprises a receptacle or box-like member for receiving a pack of manifolding forms, a writing plate hingedly secured to the box member, means for removably securing a transfer sheet or sheets on the writing plate, 40 and means for guiding individual sheets of the manifolding forms from the box member onto the upper surface of the writing plate and between the transfer sheets, whereby the form sheets may be pulled across the top of the writing plate without 45 disturbing the transfer sheets.

A preferred embodiment of our invention is illustrated in the accompanying drawings, in which

50 Fig. 1 is a perspective view of the counter sales book with cover closed.

Fig. 2 is a perspective view of the counter sales book with cover open, ready for use,

55 Fig. 3 is a perspective view of one of the transfer sheets used in the counter sales book.

Fig. 4 is a perspective view of the retaining strip

for holding transfer sheets and form sheets in position on the writing plate,

Fig. 5 is a perspective view of the guide strip for holding the form sheets in position at the bottom of the writing plate,

Fig. 6 is a perspective view of the counter sales book, showing a set of form sheets as they would appear when partly drawn from the writing plate, and the position of the writing plate during this operation,

Fig. 7 is a longitudinal sectional view on the line 1—1 of Fig. 2,

Fig. 8 is a view similar to Fig. 7, illustrating the method for pulling the form sheets across the writing plate,

Fig. 9 is a detail sectional view on the line 9—9 of Fig. 8, and

Fig. 10 is a detail sectional view on the line 10—10 of Fig. 8.

Referring now to the drawings in detail, in which like numerals refer to like parts thruout:

A box or receptacle 1, comprising a base 2, side walls 3, front wall 4, and rear wall 5, has pivotally secured to the rear wall 5 by means of hinges 6 a writing plate 7. The writing plate 7 is formed with a slot 8 adjacent the hinges 6, thru which sets 9 of a pack or deck 10 of manifolding forms may be drawn onto the writing plate 7. Transfer sheets 11, provided with reinforcing strips 12 of heavy paper or other suitable material which extend beyond the transfer sheets at either side and are formed with slots 13, are secured on the writing plate 7, between each pair of form sheets 15 in a set 9 by engagement of the slots 13 with studs 14 secured on the writing plate 7. The form sheets 15 and transfer sheets 11 are held in place and guided by a removable retaining strip 16, formed with slots 17 which engage under the beaded studs 14. Near the bottom of the writing plate 7, a second retaining strip 18 is permanently secured on the writing plate 7 by means of rivets or studs 19, and serves to hold the set 9 of form sheets 15 against the upper surface of the writing plate 7. This retaining strip 18 also serves as a guide for the sets of form sheets when they are drawn across the writing plate in process of removal, as illustrated in Figs. 6 and 8. The writing plate 7 is somewhat shorter than the length of the perforated sheets and the carbons, thus forming in cooperation with the end 7' of the plate 7 a space 20, and the form sheets 15 are of sufficient length to overhang this space 20, as indicated in Figs. 2 and 7. The overhanging edges 21 of the form sheets 15 may be easily grasped when it is desired to pull a set of form

sheets from the book. The end 4 of the box 1 is cut away at 22 to facilitate this operation. The carbons 11, of course, do not extend to the end 7 of the cover plate 7.

5 The counter sales book may be provided with a binding 23 secured on the base 2 and extended to form a cover 24 which may be folded over the writing plate and the sheets thereon, as indicated in Fig. 1, thereby protecting the sheets 10 from soiling or tearing when the book is not in use. The cover 24 may be provided with corner pockets 25, or other suitable means for removably retaining thereon a tally card or record sheet 26 for use in cooperation with the sales or form 15 sheets 15 used on the writing plate 7, as illustrated in Fig. 2.

In operation, the counter sales book is loaded by lifting the writing plate 7 and inserting a pack 20 of fold pack forms 18 in the box 1, then drawing the first set 9 of form sheets thru the slot 8. The lowermost copy or form sheet is then laid on the writing plate 7, a transfer sheet 11 laid on top with its reinforcing edge 12 engaged by the studs 14, the next lowermost copy sheet laid on the 25 transfer sheet, etc., until the original or top sheet of the set 9 is laid on the uppermost transfer sheet 11. The bottom edges 21 of the form sheets are then drawn under the retaining strip 18, and the book is ready for use, as indicated in Fig. 2. 30 After an entry has been made on the original of the set of forms, the bottom edges 21 are grasped and raised, as shown in Fig. 6. In raising the form sheets, the writing plate 7 is raised with them at the same time, due to engagement of the form 35 sheets between the writing plate 7 and the retaining strip 18. This operation provides room beneath the writing plate 7 for movement of the next set 9 of form sheets, between the pack 18 and the writing plate 7, as indicated in Figs. 6 and 8. As the first set of forms is drawn thru 40 beneath the retaining strip 18, it pulls the following set attached thereto from the pack 18 upwardly thru the slot 8 and onto the writing plate 7, without disturbing the transfer sheets 11. During this operation, the writing plate 7 rides on 45 the folds of the second set 9 of forms, as indicated in Fig. 8. When the second set of forms has been pulled thru far enough until the joint or line of weakness between the second and third set is 50 located at the slot 8 and engages the edge of the slot the writing plate 7 falls naturally back into position, as shown in Fig. 2. The first set of forms is then torn off, and the second set is in position ready for a second entry.

55 What we claim is:

1. In combination, in a counter sales book, a shallow box-like member for receiving a pack 60 of folded manifold forms, a writing and cover plate hinged at its upper edge to the box-like member and formed with a slot adjacent and parallel to its upper edge, through which the manifold forms may be drawn, means for removably attaching transfer sheets to the cover, and means for retaining the forms in place on 65 the writing and cover plate.

2. In a sales book construction for counter use, an open top manifold receiving receptacle, a cover and writing plate hinged at one end of the receptacle and formed with a slot adjacent the hinged 70 end through which manifold sheets may be drawn,

the cover plate being of less length than the receptacle for providing a space between the end of the plate opposite the hinged end and the receptacle for grasping the ends of the manifold forms which project beyond the end of the 5 cover and writing plate, a transverse bar on the said plate adjacent said space under which the manifold forms are adapted to pass, the construction and arrangement being such that when the free ends of the manifold forms are grasped to draw a set of them from the receptacle the cover may be raised, and whereby space under the cover will be provided to permit the forms to be readily withdrawn from the receptacle, as described. 10

3. In combination, in a sales book construction, of a boxlike member having an open top for receiving a pack of manifold forms, a writing and cover plate pivotally attached at its upper edge to said member and formed with a slot adjacent said upper edge, the cover plate being of less length than the boxlike member for providing a space or recess at the end of the cover plate opposite said upper edge, a spring clip 20 removably secured on said cover plate adjacent 25 said slot for holding transfer forms on the cover plate, and a bar permanently secured on said cover plate adjacent its lower edge for retaining the forms on the plate to permit the plate to be raised when the forms are drawn through the 30 opening in said plate, from the boxlike member. 35

4. In combination, in a counter sales book comprising a receptacle having an open top for receiving a pack of manifold forms having a weakened line in the forms, a cover and writing plate 40 having one edge pivotally connected to said receptacle and formed with a slot adjacent said edge, through which the forms are drawn from the receptacle, studs on said plate, a slotted spring clip member removably secured on said studs for 45 removably attaching transfer forms to the plate and located adjacent the drawing slot, a member on said plate opposite said pivoted edge for loosely holding the forms down on the plate, whereby the cover plate may be raised when the user 50 grasps the free ends of the manifold forms, and the forms drawn from the receptacle through the slot in the cover until the weakened line in the form engages an edge of the slot, when the cover plate may be permitted to fall into its 55 original position on the receptacle due to the flat arrangement of the forms in the receptacle when the line of weakness is at the slot. 60

5. In combination, in a counter sales book for zig-zag manifold forms, a boxlike receptacle having a bottom, side members, and top and bottom end members, a writing plate hinged at its top edge to the top end member of said receptacle and provided with a slot adjacent said top edge, studs on said writing plate adjacent the ends of 65 said slot, whereby transfer sheets provided with slotted transverse reinforcing strips may be removably engaged on said studs, and a transverse bar adjacent the bottom edge of said writing plate 70 permanently secured to said writing plate and spaced above the top surface of said writing plate. 75
